SELECTIVE CONTROL DEVICE.

Application filed November 8, 1920. Serial No. 422,561.

This invention relates to selective control devices, and more particularly to a device wherein any desired mechanism may be selectively controlled by the position of a swinging needle or arm.

The invention further relates to a device wherein any desired mechanism may be selectively controlled by the position of an indicating needle, adapted to assume various 10 positions in accordance with the variations of an electric current, the variations of the current being in accordance with the characteristics of the objects to be acted on by the mechanism controlled by said device.

15 It is a purpose of the invention to provide a control device, having a plurality of oppositely arranged contacts and a movable member that is adapted to bridge the gap between any pair of said contacts to complete a circuit to operate any desired mechanism in accordance with the selection of said control device, the selection being in accordance with the position of said movable member.

It is a further purpose of the invention to 25 provide a control device having a plurality of oppositely arranged contacts and a swinging needle carrying a member operating between said contacts adapted to bridge the gap between them to complete a circuit to operate any desired devices in accordance with the selection of the control device, dependent upon the position of said needle under the influence of the variations of a variable electric current.

30 It is a still further purpose of the invention to provide a device of the above mentioned character wherein one set of contacts is stationary and the other set of contacts is movable toward said stationary contacts, and 35 wherein the needle loosely supports a contact member that is adapted to be pinched or clamped between said movable and fixed contacts to complete a circuit to operate certain devices in accordance with the selection of said control device as indicated by said needle.

It is also an object of the invention to provide a selective control device having oppositely arranged sets of contacts, the number 40 of contacts of one set being a multiple of the number of contacts of the other set, whereby the number of selections of the device is multiplied without unnecessary multiplication

of the operating devices of the mechanism controlled by said control device.

It is a still further purpose of the invention to provide a selective control device, wherein any desired mechanism is operated by a plurality of electro-magnets, which are energized by an electric current, the particular electro-magnets that are energized being determined by the position of a movable contact member, relative to a plurality of oppositely arranged contacts, electrically connected with said electro-magnets, and to so construct said device as to multiply said selections without unnecessarily multiplying said electro-magnets.

It is another object of the invention to provide a selective control device operating a 70 plurality of sets of actuating devices, whereby said selections can be greatly multiplied without unnecessarily multiplying the actuating devices.

It is another object of the invention to so 75 construct the selective control device as to provide for a large number of small, closely arranged contacts, so that a large number of selections can be obtained for a small throw of the needle, and to so construct said device 80 as to avoid sparking at said contacts.

Other objects and advantages of the invention will appear as the description of the accompanying drawings, showing one form that my invention may take, proceeds. However, I desire to have it distinctly understood that I do not intend to limit myself to the exact details of structure shown in the accompanying drawings or described in the specification but desire to include as part of 85 my invention all such obvious modifications and changes in structure as would occur to a person skilled in this art and as would fall within the scope of the claims.

In the drawings:

Fig. 1 is a plan view of the selector embodied in the present invention;

Fig. 2 is a section thereof taken on the line 2—2 of Fig. 1;

Fig. 3 is a section taken on the line 3—3 of 100 Fig. 2;

Fig. 4 is a broken plan view of the needle and mounting therefor;

Fig. 5 is a section taken on the line 5—5 of Fig. 2; and

Fig. 6 is a circuit diagram showing the ar-

angement of the contacts and electro-magnets operated by said selector.

Referring in detail to the drawings, the improved selective control device comprises the casing 7 having the base portion 8 and a removable cover comprising the glass plate 9 and the holding ring 10. Mounted in the casing 7 is an indicating instrument preferably an electrical indicating instrument that is operated by the variations in an electric current passing through the same, said instrument comprising a fixed magnet having the poles 11 and a core 12 mounted between said poles 11 secured by means of the pins 13 or screws 13 to the plate 14 suitably carried in the casing. The poles 11 are suitably supported by means of the plates 15 mounted in the casing. Mounted to turn on the pivots 16 suitably journaled in the bearings 17 mounted in any suitable manner as by means of the plates 18 in the casing 7 is the coil 19 having the leads 20 and 21 extending therefrom to the binding screws 22 and 23 respectively, the magnets, binding screws and coil being suitably insulated from the casing or body portion 7 of the selective control device.

Secured to arms 24 on the supporting structure for the coil are the outer ends of coil springs 25, the inner ends of which are suitably secured to the coil 19 and tend to move the indicating member or needle 26, which is mounted to turn with the coil, to the position indicated in Fig. 1, and when a current is passing through the coil 19 this current will tend to swing the coil in a direction such that it will act against the tension of the spring and the needle 26 will move clockwise. The parts just described operate on the order of an ordinary ammeter and the position of the needle 26 will depend upon the strength of the current going through the coil 19. The indication of the needle or the position assumed thereby when a certain current passes through the coil 19, is utilized to operate certain devices in accordance with said position of the needle. While the indicating instrument is shown in the present instance as being an electrical indicating instrument, it will be obvious that the mechanism that is to be described that depends in its operation upon the position of the indicating needle would operate in the same way if the needle were an indicating member of an indicating instrument of any other kind. No matter what the nature of the indicating instrument is, the needle 26 is provided with a hook-like end portion 27 suitably closed by means of a spring or other closure member 28 with which is loosely engaged the eye 29 on a contact member 30, the contact member 30 being free to swing to the right or left as shown in Fig. 2, but due to the construction of the eye 29 and the hook 27 the same will remain substantially in alignment with the needle transversely thereof, or in a vertical direction, as

the instrument would be ordinarily placed when in use so that the needle will extend horizontally. The contact member 30 is adapted to operate between two sets or series of contacts arranged on the arc of a circle 70 and is adapted to bridge the gap between oppositely arranged ones of these contacts under certain circumstances as will be described later on. One of the sets of contacts is mounted on the plate of insulating material 31 which is mounted in any suitable manner as by means of the screws 32 on the members 15. The supporting member 31 has mounted thereon at the forward portion thereof, which is slightly depressed below 80 the main body portion of the member 31, a plurality of fixed contacts 33. Openings 34 are provided in the member 31 through which the leads 35 extend, there being one of said leads 35 for each of the contact members 33. 85 The leads 35 pass downwardly through the bottom of the instrument to suitable operating devices for operating certain mechanism that is not shown. The opposite set or series of contacts is mounted on a plate or block 90 of insulating material 36, which has secured thereto guide rods 37 which pass through guide members 38 mounted on the casing 7, and which have secured thereto by means of a set screw the fixed collars 39, the member 36 95 with its contacts being movable as a unit toward and away from the member 31.

Mounted to slide on the rods 37 is the yoke 40 which is provided with eyes 41 and 42 connected by means of the bight portions 43, 100 which are adapted to receive the guide rods 37. Mounted between the collars 39 and the portions 41 of the yoke 40 are the coil springs 44 which are adapted to be compressed when the yoke 40 is moved toward the body of the 105 instrument. The ends of the guide members 38 are adapted to be engaged by the portions 42 of the yoke after the same have moved through a certain distance. The yoke 40 is actuated by means of the rod 45, which is periodically operated by mechanism that is not shown. The rod 45 is guided through the cylindrical guide member 46 provided on the bracket 47 secured at 48 to the casing 7, and is also guided through the bushing 49 provided in the casing 7. The yoke 40 is provided with a boss 50 through which the rod 45 passes, and to which the same is secured by means of a set screw 51. Mounted between the boss 50 and the bushing 49 is the 115 coil spring 52. The operation of the parts just described is as follows:

When the rod or wire 45 is operated so as to move from the right to the left as shown in Figs. 1 and 2, the coil spring 52 is compressed between the members 49 and 50, and the yoke 40 is moved toward the left compressing the springs 44 on the rods 37, and after these have been compressed to a certain extent the pressure of the springs against 120

- the collars 39 will cause the rods 37 to travel with the yoke 40 toward the left. The movement of the yoke is limited by the contacting of the member 42 with the end of the member 38. The parts will be held in this position as long as the force exerted on the rod or wire 45 acts in the direction from right to left. When the force exerted on the wire is removed, the spring 52 and the springs 44 will tend to return the parts to their normal position, and the boss 53 on the member 46 will limit the movement of the yoke 40 toward the right.
- 10 Mounted in a recess in the member 36 and suitably insulated from each other, as will be clear from Fig. 2, are the contact plates 54, 55 and 56. The contact plate 54 is provided with contact members 57 extending toward the contacts 35 and spaced equidistantly along the edge of the plate 54. The contact plate 55 is provided in a similar manner with the contact members 58 and the plate 56 with the contact members 59. Upon referring to Fig. 5 it will be seen that the extreme end portions of the contact members 57, 58 and 59 are arranged in alignment and lie in the same plane as the central contact plate 56. Each of the contact plates is provided with a suitable lead extending to suitable operating mechanism for operating a mechanism that is not shown in the drawings. The operation of the instrument is as follows:
- 15 An object that is to be operated on by the selectively control mechanism is manipulated so as to produce a certain current effect in the circuit of which the coil 19 is a part, thus causing a certain indication by the needle 26, the needle 26 moving to a certain defined position between the sets of contacts 35 and 57, 58 and 59 depending upon the effect produced on the instrument by the object referred to. The rod or wire 45 is actuated after the needle has had time to come to rest in its proper position by means of certain mechanism that is not shown, so as to move the movable contact carrying member 36 toward the fixed contact carrying member 31, so as to clamp the contact member 30 carried by the needle 26 between certain of the contacts mounted on the fixed and movable contact carrying members, the particular contacts between which the member 30 is pinched or clamped being dependent upon the position of the needle and directly related to the effect produced by the object above referred to on the indicating instrument of which the needle is a part. The parts are held in this position under a spring pressure for a certain length of time during which an operating circuit is mechanically closed in a manner that is not shown, so that a current will pass through the lead 35 associated with the particular contact 33, with which the contact member 30 is then engaged, through
- 20 the contact member 30 and through one of the contacts 57, 58 or 59, and through the lead associated with the contact plate of which the particular contact member 57, 58 or 59 is a part, to actuate certain operating means 70 that are associated with the particular leads just described, so as to selectively control the operation of mechanism that is to operate on the object that has been used to influence the indicating instrument. After these devices have been operated, the operating circuit is again mechanically opened, after which the pressure on the rod or wire 45 is released to allow the separation of the contacts and the release of the contact member 80 30, after which another object may be brought up to again effect the instrument and operate the various devices above referred to in a manner corresponding to the effect produced on the instrument by that particular object. 85
- 25 Referring to the diagram shown in Fig. 6, the operating circuit comprises the wires 61 and 62 leading from any suitable source of current, in one of which is provided the switch 63, which may be assumed as being 90 the means for mechanically opening and closing the circuit just referred to. In the diagram shown in Fig. 6 only two contacts 33 are shown and only two of each of the contacts 57, 58 and 59. In the instrument described above, there are only two different arrangements of contacts, although a much larger number of contacts is shown. In Fig. 6 the wire 61 is shown as having the branches 95 64 and 65, the branch 64 having an electro-magnet 66 in circuit therewith. If in the arrangement shown in Fig. 6 the contact making member 30 were in a position opposite a contact 33, with which the electro-magnet 66 is associated, and opposite one of the contacts 57, 58 or 59 when the circuit is closed by means of the switch 63, the electro-magnet 66 associated with the branch 64 will be actuated so as to operate any suitable mechanism 100 associated therewith. At the same time certain other mechanism will be operated to vary or modify the operation of the mechanism set in motion through the actuation of the electro-magnet 66 depending upon the position of the member 30 relative to the contacts 57, 58 105 and 59.
- 30 It will be noted that in the diagram the contact 57 is shown as having a lead 67 connected thereto, which lead is a branch off 110 from the lead 62, and that the contact 58 has a lead 68 connected with the lead 62, and having the electro-magnet 70 in series therewith. In a similar manner the contact 59 has the lead 69 and the electro-magnet 71 associated 115 therewith. It is of course understood that the plates 54, 55 and 56 form parts of the circuit designated by the leads in the diagram in Fig. 6. If the contact 30 is in the position shown in Fig. 6 when the movable contacts are moved to clamp the same between 120
- 35 125
- 40 130

them and the fixed contacts, and the circuit is closed by means of the switch 63, the current will pass through the leads 64 and 67 and only the electro-magnet 66 will be effected thereby, thus the effect produced on the mechanism will be solely dependent upon the operation of the electro-magnet 66 and any positive operating devices that may be set in operation when the electro-magnets 70 and 71 are not being operated. If the contact member 30 is located between a contact 58 and the contact 33, the electro-magnets 66 and 70 will be both set in operation by the current passing through the same, and the effect produced on the mechanism controlled thereby will be the combined effect of these two electro-magnets. In a similar way if the contact member 30 were located between the contact 33 shown in the left of Fig. 6, and the contact 59 associated therewith, the electro-magnets 66 and 71 would be operated to effect the operation of the mechanism by the combined effect of the devices actuated thereby. It will thus be seen that for each contact 33 and magnet 66 associated therewith, a certain operation of the controlled mechanism can be produced, and that by the plurality of contacts associated with each contact 33 the selections of operations that can be obtained by the electro-magnet 66 can be multiplied the same number of times as there are contact members associated with each contact member 33, in the present instance there being three. It is not necessary that all of the contacts 33 have an electro-magnet 66 associated therewith as a lead 65 can be provided that does not have an electro-magnet 66 in series therewith. Instead of providing for electro-magnetically operated control means in this instance mechanical or positively acting means can be provided which can be modified by the operation of the devices controlled by the electro-magnets 70 and 71 in the manner described for a contact 33 with which an electro-magnet 66 is associated. In this instance, however, it is not necessary to connect the contact member 57' electrically with the lead 62, as if this were done it would merely act to short circuit the device without producing any desirable result, as to lead the current through the members 67 would produce the same result on the operating mechanism as to not have any current passing therethrough. In other words, the contact member 57' is positively operated and when the contact member 30 is in position to bridge the gap between the member 33 and the member 57' associated therewith, no operation of electrical devices takes place, but the mechanism is merely operated mechanically. This has been found to be of advantage in providing a positively operating mechanism that can be selected by the instrument, and which will also operate in case the instrument does not properly operate so that the object that is effecting the instrument at the time that it fails to operate or which does not produce any effect on the instrument due to its inherent qualities, may be discharged from the mechanism which operates upon objects that fall within the range of the selective control devices. By providing this discharge position any article that would not effect the selective control device is prevented from remaining in the mechanism controlled thereby, and interfere with the operation of the same.

While the device just described may be used for selectively controlling any mechanism, it has been found to be of particular advantage in selectively controlling a sorting mechanism, such as is described in my copending application Serial No. 419,848, filed Oct. 27, 1920, Patent #1,396,221, dated Nov. 8, 1921, in which the indicating instrument is operated by means of an amplified current, the variations in which are produced due to the effect on a photo electric cell of the objects that are to be sorted.

From the above it will be seen that a selective control device has been provided that is compact, and that can produce a very large number of selections without an undue multiplication of the actuating devices, which in the present case are shown as being electro-magnets, and that a device is provided that is positively operating and that is so constructed that the current will not pass through the small contacts of the instrument until the same have been positively brought together so that no sparking or arcing will occur at these contacts, thus preventing damage to the contact points in this manner.

Having thus described my invention what I desire to claim and secure by U. S. Letters Patent is:

1. A selective control device comprising a controlling circuit, a set of contacts, a plurality of operating circuits electrically connected therewith, a second set of contacts arranged opposite said first set, a plurality of operating circuits electrically connected therewith, electro-magnets in certain of said operating circuits of each set, certain of said circuits having no electro-magnets therein and a movable contact making member operating between said sets of contacts and adapted to co-operate with any opposite pair of said contacts to serially connect an operating circuit associated with one of said sets of contacts with an operating circuit associated with the other of said sets of contacts to throw either two of said electro-magnets into operation simultaneously or one of said electro-magnets singly.
2. A device for selectively controlling the simultaneous operation of a plurality of electro-magnetic devices comprising a plurality of operating circuits certain of said circuits

- each serially including one of said devices, said circuits being arranged in two sets the circuits of each set being connected in parallel, and means for selectively serially connecting any one of the circuits of one of said sets with any one of the circuits of the other of said sets, comprising a set of contacts forming the terminals of one of said sets of circuits, a set of contacts forming the terminals 70 of the other set arranged opposite said first set of contacts, and a movable contact member adapted to bridge the gap between opposite pairs of said contacts to connect any one circuit of one set with any one circuit of the other set to simultaneously energize a pair of said electro-magnets.
6. A selective control device comprising an indicating instrument, having an indicating member, a contact making member loosely hung from said indicating member, oppositely arranged sets of contacts, said contact making member operating between said sets of contacts, and means for moving said contact making member into a position therebetween in accordance with the indications of said instrument.
7. A selective control device comprising an indicating instrument, having an indicating needle, a contact making member pivotally suspended from the end portion of said needle, oppositely arranged sets of contacts, said contact making member operating between said sets of contacts, and means for moving said contact making member into a position therebetween in accordance with the indications of said instrument.
8. The combination with a series of devices for operating on a succession of objects in accordance with a varying characteristic thereof, of a selective control device for said devices, comprising a series of operating contacts progressing in a given direction and each associated with one of said devices, a movable contact making member adapted to move progressively along said series and assume various positions relative to said series of contacts, a second set of operating contacts 95 comprising a plurality of repeating series of contacts, each of said last series of contacts being arranged so as to progress in the same direction as said first series and means for moving said movable contact making member 100 into a position with relation to said operating contacts dependent upon the characteristic of each of said objects.
9. The combination with a series of devices for operating on a succession of objects in accordance with a varying characteristic thereof, of a selective control device for said devices, comprising a series of operating contacts progressing in a given direction and each associated with one of said devices, a 115 movable contact making member adapted to move progressively along said series and assume various positions relative to said series of contacts, a second set of operating contacts comprising a plurality of repeating series of contacts, each of said last series of contacts being arranged so as to progress in the same direction as said first series there being as many repeating series of contacts as there are contacts in said single series, and means for 120 125 130
10. of the other set arranged opposite said first set of contacts, and a movable contact member adapted to bridge the gap between opposite pairs of said contacts to connect any one circuit of one set with any one circuit of the other set to simultaneously energize a pair of said electro-magnets.
11. A permutative selector comprising a source of electric current, a pair of conductors leading from said source of current, one of said conductors having a plurality of branches 75 connected therewith, each of said branches terminating in a contact member, said contact members being arranged in a single progressive series the other of said conductors having a plurality of branches, a plurality of 80 contacts opposite said first mentioned contacts, said contacts being arranged in repeating sets, one of said sets being opposite each of said first mentioned contacts and the contacts in each set being correspondingly arranged in a series progressing in the same direction as said first series and the corresponding contacts of all the sets being connected to the same branches of said second conductor, and a movable contact member 85 adapted to bridge the gap between any opposed pair of said contacts to serially connect any one of said first branches with any one of said second branches.
12. The combination with a series of devices 90 for operating on a succession of objects in accordance with a varying characteristic thereof, of a selective control device for said devices, comprising a series of operating contacts progressing in a given direction and each associated with one of said devices, a movable contact making member adapted to move progressively along said series and assume various positions relative to said series of contacts, a second set of operating contacts 95 comprising a plurality of repeating series of contacts, each of said last series of contacts being arranged so as to progress in the same direction as said first series and means for moving said movable contact making member 100 into a position with relation to said operating contacts dependent upon the characteristic of each of said objects.
13. A device for selectively controlling the simultaneous operation of a plurality of electro-magnets comprising a plurality of operating circuits, certain of said circuits each serially including one of said electro-magnets, said circuits being arranged in two sets, the circuits of each set being connected in parallel and means for selectively serially connecting any one of the circuits of one of said sets with any one of the circuits of the other of said sets, comprising a set of contacts forming the terminals of one of said sets of circuits, a set of contacts forming the terminals of the other set arranged opposite 110 said first set of contacts, and a movable con-

moving said movable contact making member into a position with relation to said operating contacts to bridge an opposite pair thereof dependent upon the characteristic of each of 5 said objects.

10. A control device comprising a plurality of spaced oppositely arranged sets of contacts, and a movable member adapted to selectively bridge the gap between pairs of said 10 contacts, whereby controlled mechanism is operated in accordance with the selection of said control device, the number of contacts of one set being a multiple of the number of contacts of the other set and being arranged in 15 groups opposite said other set, said groups being all duplicates in both number and progressive arrangement to multiply the selections of said other set.
11. Apparatus of the character described 20 comprising a movable pointer, and means for selectively functioning in accordance with the different positions occupied by said pointer,

said means including a contact element loosely carried by said pointer.

12. A selective control device comprising a 25 member swingable on an axis, spaced rows of contacts arranged concentrically relative to said axis and a movable contact member pivotally carried by said swingable member and extending between said rows of contacts substantially parallel to said axis.

13. A selective control device comprising a 30 member swingable on an axis, spaced rows of contacts arranged concentrically relative to said axis and a movable contact member pivotally carried by said swingable member and extending between said rows of contacts substantially parallel to said axis, one of said rows of contacts being movable toward and away from said other row substantially longitudinally of said swingable member.

In witness whereof I hereunto subscribe my name this 3rd day of November, A. D., 1920.

LESTER L. LADD.
